UNITED STATES PATENT OFFICE

106,812

DESIGN FOR A COMBINED WATER COOLER AND DISPENSER

Guido J. Wiggenhorn, Los Angeles, Calif.

Application April 7, 1937, Serial No. 68,594

Term of patent 7 years

To all whom it may concern:

Be it known that I, Guido J. Wiggenhorn, a citizen of the United States, residing at Los Angeles, in the county of Los Angeles and State of California, have invented a new, original, and ornamental Design for a Combined Water Cooler and Dispenser, of which the following is a specification, reference being had to the accompanying drawings, forming part thereof in which:

Figure 1 is a front elevation and Figure 2 is a side elevation of a combined water cooler and dispenser showing my new design.

I claim:

The ornamental design for a combined water cooler and dispenser, as shown.

GUIDO J. WIGGENHORN.
